UNITED STATES PATENT OFFICE.

JOHN C. MCINTYRE, OF FARNHAM, NEW YORK, ASSIGNOR TO THE SPRAGUE MANUFACTURING COMPANY, OF SAME PLACE.

CAN-WIPI NG MACHINE.

SPECIFICATION forming part of Letters Patent No. 550,379, dated November 26, 1895.

Application filed July 31, 1895. Serial No. 557,683. (No model.)

To all whom it may concern:

Be it known that I, JOHN C. MCINTYRE, a citizen of the United States, residing at Farnham, in the county of Erie and State of New York, have invented a new and useful Improvement in Can-Wiping Machines, of which the following is a specification.

This invention relates principally to machines for wiping the tops of filled cans preparatory to attaching the caps thereto.

The main object of my invention is to produce a simple and efficient mechanism whereby the cans are propelled through the machine with a rotary movement.

Other objects of my invention are to improve the details of the machine.

In the accompanying drawings, consisting of two sheets, Figure 1 is a rear elevation of my improved can-wiping machine. Fig. 2 is an end elevation thereof. Fig. 3 is a vertical cross-section in line 3 3, Fig. 1. Fig. 4 is a horizontal section thereof in line 4 4, Fig. 1. Fig. 5 is a vertical section on an enlarged scale in line 5 5, Fig. 2. Fig. 6 is a fragmentary top plan view, on an enlarged scale of the conveyer operating upon a can. Fig. 7 is a fragmentary vertical section in line 7 7, Fig. 6.

Like letters of reference refer to like parts in the several figures.

The main frame of the machine is constructed in any suitable manner, and may consist, for instance, as shown, of two end frames A A', connected by longitudinal bars 35 a and provided at their upper ends with front and rear supporting heads or standards B B', respectively.

C represents a feed-trough, from which the filled cans are delivered to the carrying mechanism. This trough is arranged transversely at the front end of the machine and connected with the adjacent end frame. The cans are carried along the trough by means of a chain belt c, which is arranged with its carrying portion in a longitudinal groove formed in the top of the trough and passes, with its receiving and delivery portions, respectively, around sprocket-wheels c' c², journaled on the under side of the feed-trough. The rear 50 portion of the feed-trough is preferably some-

what lower than the front portion, and the cans are placed in a tilted position with their central portions resting on the feed-belt and with one side of the bottom resting on the depressed portion of the feed-trough, thereby 55 enabling the cans to be carried over the trough with the least resistance. The rear side of the trough is provided with a guide-rail c³, which is connected with the trough by posts c⁴, and against which the rear sides of 60 the cans rest in passing along the trough in an inclined position.

D represents a number of longitudinal supporting-rollers, which receive the cans from the feed-trough and on which the cans rest 65 with their bottoms during the operation of brushing the tops thereof. These rollers are arranged parallel, side by side, so as to form a suitable support for the cans, and are journaled with their front and rear ends in bearings formed in the front and rear heads B B'. E represents a conveyer, which is arranged lengthwise above this can-support and on the rear side thereof, and whereby the cans are carried lengthwise over the support and past 70 the wiping device F, which is arranged at a suitable height above this support. This can-conveyer consists, preferably, of a shaft e and a skeleton screw e', arranged around the conveyer-shaft and connected therewith at intervals by radial supporting-arms e². It is obvious, however, that this screw conveyer may be constructed in various ways.

The supporting-rollers are rotated by suitable mechanism to move rearwardly with their 85 upper portions, whereby the cans resting upon the same are caused to hug the screw conveyer and are retained in the spaces between the convolutions of the screw while being propelled forward by the same. Motion is 90 transmitted to the supporting-rollers, preferably from a counter-shaft f, by gear-pinions f', secured to the supporting-rollers in front of the front head, idler gear-pinions f², journaled on the front head and meshing with the adjacent roller gear-pinions f³, and an idler gear-pinion f⁴, mounted on the counter-shaft and meshing with the gear-pinion of the foremost supporting-roller.

The feed-belt of the feed-trough is driven 100

by a gear-wheel f^4 , secured to the shaft of the delivery sprocket-wheel c^2 of said belt and meshing with the idler gear-pinion f^3 . Motion is transmitted from the conveyer-shaft 5 to the counter-shaft by a chain belt f^5 , passing around sprocket-wheels $f^6 f^7$, secured, respectively, to the conveyer-shaft and the counter-shaft f . Upon turning the conveyer in the proper direction the cans are carried 10 lengthwise over the supporting-rollers from the front to the rear ends thereof, and while the cans are being thus carried they are firmly held in engagement with the conveyer by the constant rearward movement of the upper 15 portions of the supporting-rollers. When the can has entered into one of the spaces which the convolutions of the conveyer-screw present on the front side of the conveyer, the can bears against the screw at two points g and g' , as represented in Figs. 6 and 7, the point g being located on the advancing side of the can and the point g' in rear thereof. On the advancing side of the can the latter bears against the lower portion of the conveyer-screw, which moves toward the rear 20 side of the machine, and at the other contact-point the can bears against the upper portion of the screw, which moves toward the front side of the machine. At both contact-points 25 the movement of the screw is therefore such as to turn the can about its axis backwardly on its rear side, which is in contact with the screw, and forwardly on its front side. The direction of movement of these parts is indicated by the arrows in Figs. 6 and 7. The 30 rotary movement which is imparted to the can presents all portions of the tops and of the groove in the same to the brushing, wiping, or other mechanism which operates upon the 35 can.

The conveyer is preferably driven from a main shaft H , journaled in the upper portion of the front standard by a chain belt h , passing around sprocket-wheels $h' h^2$, secured, respectively, to the main shaft and the conveyer-shaft, as shown in Fig. 1.

I represents a rear guide or cushion arm, whereby the speed of the cans as they are carried rearwardly by the feed-belt and supporting-rollers is checked, thereby preventing 50 the cans from coming suddenly in contact with the conveyer and spilling their contents. This arm is arranged obliquely between the supporting-rollers and the conveyer in the 55 path of the cans as they issue from the feed-trough, and is pivoted at its rear end to a supporting-rod i on the frame, so as to swing horizontally. The cushion-arm is yieldingly held in its foremost position by a spring i' , secured with its ends to a hook i^2 , formed on the arm, and a collar i^3 , which is adjustably secured to the supporting-rod i . The forward 60 movement of the cushion-arm is limited by a stop i^4 , which is arranged on the supporting-rod and against which the hook of the cushion-arm is adapted to engage. The delivery por-

tion of the feed-trough is preferably provided on its front side with a short guide-rail i^5 , which directs the cans against the cushion-arm. The latter also serves to aid in guiding the 70 cans into the flights of the conveyer in addition to checking the movement of the cans as they approach the conveyer.

J represents a front guide-arm, which aids in directing the cans against the conveyer as 75 they are delivered from the feed-trough upon the supporting-rollers. This arm is arranged transversely over the front supporting-rollers at the delivery end of the rear guide-rail in such a position that the cans upon striking 80 the same will be deflected rearwardly toward the conveyer. This guide is attached to the upper end of a vertical shaft j , which is journaled in bearings on the rear post of the guide-rail. The front guide-arm is yieldingly held 85 in its normal position against a stop j' , formed on the rear end of the rear guide-rail by a spring j^2 , secured with one end to the under side of the feed-trough and with its opposite end to an arm j^3 , secured to the lower end of 90 the shaft j . The guide-arm stands normally with its rear end at such a distance in front of the conveyer that when the can has been placed properly in the bight of the conveyer the can will clear the rear end of the arm; but 95 the latter will not permit the can to pass between the salient portion of the conveyer and the rear end of the arm. Should a can become caught between the conveyer and the guide-arm, the latter yields and so allows the 100 can to pass onward and at the same time exerts an inward pressure against the can and so directs the same into the next following bight of the conveyer, thereby preventing 105 jamming or crushing of the cans and injury to the machine.

The revolving brush F is arranged lengthwise over the path of the cans and is mounted on a longitudinal shaft k , which is preferably supported in such manner that the brush can 110 be adjusted up and down and forward and rearward as may be necessary to enable the brush to operate upon cans of different sizes. For instance, as shown, the shaft k is journaled in bearings k' , which are adjustably secured in any suitable manner in inclined slots k^2 , formed in the upper portions of the standards. The brush is driven by means of a chain belt k^3 , passing around sprocket-wheels $k^4 k^5$, mounted, respectively, on the driving-shaft and the brush-shaft, sufficient slack being allowed in said belt to permit of the necessary adjustment of the brush.

L represents a delivery-trough, which is arranged at the rear end of the supporting-rollers, and which receives the cans from the same after the tops thereof have been cleaned by the brush.

M is a guard-rail, which is arranged in front of the delivery portion of the conveyer, and 125 which is supported on the rear standard of the frame. This guard-rail bears against the

front sides of the cans, which are engaged with the delivery portion of the conveyer, and holds the same in engagement therewith, thereby compelling the cans to move forward 5 and preventing the same from being forced away from the conveyer and thrown forwardly over the supporting-rollers by reason of an accumulation of cans in the delivery-trough, which interferes with the free forward movement of the cans.

N represents a hood or cover, of sheet metal or other suitable material, which covers the brush.

I claim as my invention—

1. The combination with a supporting frame, of a screw conveyer, supporting rollers upon which the cans rest, and mechanism whereby said rollers are rotated to move with their upper portions toward the conveyer and 20 hold the cans in engagement therewith, substantially as set forth.

2. The combination with a supporting frame, of a screw conveyer, can supporting rollers rotating with their upper portions toward the conveyer, and a rotating brush arranged above the supporting rollers, substantially as set forth.

3. The combination with a supporting frame, of a rotary brush, a screw conveyer 30 whereby the cans are carried past the brush, can supporting rollers rotating with their upper portions toward the conveyer, and a yield-

ing guide arranged adjacent to the front portions of the supporting roller, substantially as set forth.

4. The combination with a supporting frame, of a rotary brush, a screw conveyer 35 whereby the cans are carried past the brush, can supporting rollers rotating with their upper portions toward the conveyer, and a yielding guide arranged obliquely between the supporting rollers and the conveyer, substantially as set forth.

5. The combination with a supporting frame, of a rotary brush, a screw conveyer 45 whereby the cans are carried past the brush, can supporting rollers rotating with their upper portions toward the conveyer, a feed trough which delivers the cans to the supporting rollers, a yielding guide arm arranged 50 over the front portion of the supporting rollers adjacent to one side of the feed trough, and a yielding guide arm arranged between the supporting rollers and conveyer and extending obliquely from the opposite side of 55 the feed trough to the rear portions of the supporting rollers, substantially as set forth.

Witness my hand this 29th day of July, 1895.

JOHN C. MCINTYRE.
